UNITED STATES PATENT OFFICE.

ISIDORE MARKS, OF DORCHESTER, MASSACHUSETTS.

DESIGN FOR A CLAPPER NOISE-PRODUCING TOY OR ANALOGOUS ARTICLE.

Application filed May 13, 1927. Serial No. 21,966. Term of patent 7 years.

To all whom it may concern:

Be it known that I, ISIDORE MARKS, a citizen of the United States, residing at Dorchester, in the county of Suffolk and Commonwealth of Massachusetts, have invented a new, original, and ornamental Design for a Clapper Noise-Producing Toy or Analogous Article, of which the following is a specification, reference being had to the accompanying drawing, forming a part thereof.

In the accompanying drawing:

Figure 1 is a view, in front elevation, and Fig. 2 is a view, in side elevation, of a clapper noise-producing toy showing my new design.

The dominant feature of the design is the surface ornamentation on the clapper of the toy.

I claim:

The ornamental design for a clapper noise-producing toy, or analogous article, substantially as shown and described.

ISIDORE MARKS.
